UNITED STATES PATENT OFFICE.

JOHN GUSTAFSON, OF ROCKAWAY, NEW JERSEY, ASSIGNOR OF ONE-HALF
TO GARDINER G. HUBBARD, OF WASHINGTON, DISTRICT OF COLUMBIA.

TYPE-SETTING MACHINE.

SPECIFICATION forming part of Letters Patent No. 453,257, dated June 2, 1891.

Application filed January 20, 1891. Serial No. 378,442. (No model.)

To all whom it may concern:

Be it known that I, JOHN GUSTAFSON, a citizen of the United States, and a resident of Rockaway, Morris county, New Jersey, have 5 invented a new and useful Improvement in Type-Setting Machines, which improvement is fully set forth in the following specification.

The present invention relates to the construction of machines for composing or setting type, and particularly to that form of machine which manipulates ordinary type, such as are in universal use. Machines of this character as heretofore constructed have required power for their operation and are somewhat costly and complicated. For an example of such a machine reference may be had to Letters Patent No. 427,685, granted to me May 18, 1890.

20 The presence of shafts and belting in the composing-room of a printing establishment is not desirable and often is difficult to obtain. Moreover, it is evident upon reflection that, since the rapidity of the operation must 25 depend upon the quickness of the compositor's eye and hand in reading his copy, seizing the proper type, and depositing it in the receptacle of the machine, the gain in speed that can be effected by a power-driven machine is not productive of a gain in the operation of composing after the limit of speed which the compositor's skill determines has 30 been passed. The transfer of the copy to type necessarily requires a mental and a manual operation for each individual character, and this fact fixes a practical limit to the advantage derivable from type-setting or composing machines of every sort. It follows that the greatest room for industrial improvement in this art lies not in the direction of expediting the machine operations, but in reducing, so far as possible, the cost and complexity of the mechanical devices which perform all the steps of the operation except 35 those which actually require and employ the intelligence and manual dexterity of the compositor.

This is the general object of the present invention; and, more specifically, its object is to 40 produce a type-setting or composing machine

which can be operated by the hand of the compositor, and which will with certainty and precision set the type properly in the composing-stick as fast as the compositor using his right and left hands alternately can deposit them (without regard to the position of the nick) in the hopper or receptacle provided for the purpose.

To render such a machine practically and commercially successful, the following conditions are deemed essential or important and are provided by the present invention: First, the mechanism should be extremely simple and so constructed as to give rise to no difficulties in management and not to be liable to derangement in the hands of operators unaccustomed to mechanical contrivances; second, it should be small in size, so as not to interfere with the operator's use of his case, and of little weight, so as to be conveniently carried from place to place; third, it should require a very slight expenditure of strength in its operation, so as not to entail additional fatigue; fourth, the power should be derived in such manner as to require of the operator no movements or maneuvers additional to those usual in composing or which would divert his attention from the operation of setting type.

Heretofore in constructing machines of this sort it has been deemed essential to provide mechanism for reversing such type as might be thrown into the hopper wrong end up. This mechanism constituted a large portion of the machine and demanded for its operation the major part of the power used in driving the same. It is found that the gain in speed effected by this mechanism is very slight and that it can be omitted with decided advantage. In composing, the operator necessarily throws his eye to the box containing the letter his hand is about to grasp and singles out the most prominent type. This is part of his training, and in grasping it he loses little or no time in taking it by the face end. The operation that creates delay in transferring the type from its box to its proper position in the stick is the turning of the type so that it will stand "nick out." This operation, moreover, is one for which the

left hand is not adapted. According to the present invention, therefore, the only operation to be performed is to transfer the type from the outlet of the hopper to the stick and during this movement to turn it so that its nicked side will be exposed. This turning is effected by a series of trippers, as heretofore. The construction of the trippers, however, has been greatly simplified. Heretofore the type was fed past the entire series of trippers at a single motion, and consequently at high speed. To avoid as much as possible the excessive wear and injury to the type incurred by striking with considerable force against the corner of the tripping-teeth, the latter were necessarily made quite thick, so as to distribute the pressure and shock over a considerable length of the type. Using a tooth much wider than the nick, it had to be pivoted so as to swing in and out of operating position, according as the type required to be turned or not, and to actuate the tripping-tooth a controlling device was provided, which was acted upon by the type in advance of the tripper to throw out the latter when the type came with one of the three plane sides out. To keep proper pressure on the type while undergoing these operations required a comparatively powerful spring, which was also needed to prevent the type from turning more than a quarter when it encountered a tripping-tooth at the rate of speed given to it. To overcome the resistance thus produced demanded considerable power, and this fact alone would render impracticable the employment of such a system of trippers in a hand composing-machine.

According to the present invention the type, instead of being carried at a single rapid movement through the entire tripping system, comes to a stop just in front of each tripping-tooth. Consequently it is acted upon by the latter just as its advance motion begins and its momentum is at the minimum. The removal of complicated mechanism which this change renders possible permits the location of the trippers much closer together than heretofore. The motion of the type at each feed is one-half an inch, or less than one-sixth of the motion of the previous machine. The difference in speed is still greater. For these reasons a very light spring will hold the tripper in action against the type, and the width of the tripping-tooth can be reduced so that it will lie in the nick of the type, and it thus becomes possible to employ tripping-teeth which are rigidly fixed to their support.

For the purpose of moving the feed-slide against the slight resistance offered by a system of trippers such as above described very little power is required. This is furnished by a hand-lever, which the compositor presses in one direction each time he deposits a type and which is returned by a spring. This lever stands just behind the funnel or hopper, and has two branches projecting, respectively, on opposite sides thereof. As the composi-

tor's hand (either right or left) brings a type from the case to the hopper his disengaged fingers (which in ordinary composing are not used) encounter either the right or left branch of the lever and press the latter toward him, thus making a feed. The form and relative position of the lever and hopper are such that when the former reaches its stop the fingers holding the type will be just above the hopper. The lever thus guides the hand to the hopper, and in practice it is not necessary for the compositor to glance at the hopper at all. The work of depressing the lever is not more fatiguing than operating the keys of a type-writer, and the movement is easier. As the compositor uses both hands and arms alike, his position is much less constrained and awkward than in ordinary composing.

The present invention includes improvements in the feed-slide and means for guiding the same and improvements in the means for actuating the alarm-signal, as well as certain novel details of construction and combinations of parts, as hereinafter set forth.

The several improvements combined and organized as herein shown and described constitute a complete composing or type-setting machine, whose extreme length, including the composing-stick, is under nine inches, and which weighs complete about one and one-half pound.

The accompanying drawings, which form a part of this specification, represent a machine constructed in accordance with the invention.

Figure I is a plan view; Fig. II, a front elevation; Fig. III, a top view showing the position of the parts when the actuating-lever is moved forward. Fig. IV is a rear view of the machine reversed. Fig. V is a detail of the bell movement; Fig. VI, details of the guide-grooves; Fig. VII, details of the funnel and connected parts; Fig. VIII, a detail of the gate opening to the composing-stick; Figs. IX and X, details of the trippers; Fig. XI, a detail of the guide-pin; Fig. XII, a detail of parts beneath the funnel, and Fig. XIII a detail of the feeding devices.

The various devices are supported by a back plate A, which is designed to be fixed by screws to the front bar of the ordinary composing-frame directly under the space-box. To this support is attached a plate B, inclined from the horizontal. The attachment is effected by means of a screw a, passing through a slot in the vertical flange B' of plate B and tapped into the support A. Plate B can thus be adjusted with reference to its support for the purposes hereinafter described.

Upon plate B are two upright parallel bars C D, which constitute the sides of the composing-stick. The bar C is adjustably secured to the plate B by means of screws c, so that the width of the column can be varied. The side or ledge E, along which the type is fed toward the composing-stick, is fastened to the back plate A by means of screw-pins d e.

The feed-slide F is made of sheet metal

folded over so as to embrace the ledge E. It carries type-feeding fingers f and g. Fingers f are three in number, all made of strips of steel folded over and projecting beyond the ledge E, both above and beneath the same, so as to push forward the type when the slide moves to the left. Fingers g are, as shown, made in one piece with the slide, and they serve to give to the type its first motion, carrying it out from under the funnel-shaped receptacle or hopper G, in which it is placed by hand. The extremities g² of the slide give the type its last movement. Hopper G is supported in a socket H, attached to the screw-pin d.

I is the operating-lever by which the feed-slide is reciprocated. Its shape resembles a letter Y, and, being placed just in front of hopper G, its two branches, which are provided with pads or cushions I', lie in the way of the compositor's fourth and little fingers as he carries the type from the case to the hopper. Lever I is fulcrumed on a pin h, carried by a bracket i, attached to the fixed sill E, and a spring j, coiled around pin h, maintains the lever normally in the position shown in Fig. I. Motion is communicated to the feed-slide through an elbow or bell-crank lever, which is fulcrumed on the upright screw-pin e. One arm k of this lever is connected to a link K, whose other end connects with the operating-lever I. The connections of the extremities of link K are by ball-and-socket joints. The other arm k' of said lever is pivoted to the end of a link L, whose other end is pivotally attached to the feed-slide F.

When, in the act of depositing a type in the hopper, the compositor moves lever I forward, the feed-slide F moves toward the composing-stick, carrying the type forward one step. At the end of this motion the parts occupy the positions shown in Fig. III. When the compositor removes his fingers from the lever I to take up another type, spring j returns the lever and feed-slide to their normal positions.

When the feed-slide returns for another feed, it describes a curve, so that its fingers f g may clear the type then in transit to the composing-stick. The motions of the slide are controlled by the spring guide-pins l and the grooves or guideways m m' in the ledge or sill E, (see Fig. VI,) by which the pins are confined and guided. In moving to the left—that is, in making a feed—the pins l follow the straight grooves m, and in returning they follow the curved grooves m'. The construction of the pins l is shown in Fig. XI. Each pin has a rounded head, which runs in the groove, and a stem, which enters a hollow pillar l' on the feed-slide F and bears at its upper end against the head of a similar pin n, around whose shank is coiled a small spiral spring n'. In order that the pins l may be switched from the straight into the curved grooves, and vice versa, a step is formed at the intersection of these grooves at each end—

that is to say, the straight groove m is inclined upward, being lower at its first end and higher at its last end than the curved groove m', whose bottom is in a horizontal 70 plane. Consequently pins l must take the straight groove in advancing and the curved groove in returning.

When the type falls into the hopper, it comes to rest upon the top of plate B. The 75 lower end of the type is then confined on one side by the curved end of a bar o, fixed to screw-pin O by a set-screw and adjustable vertically thereon, and on the other side by a light spring o'. The upper end of the type is 80 confined by the walls of the funnel G and by a swinging gate L', carried by an arm M, attached to screw-pin d, and closed by a small spring N. This gate is opened as the feed-slide advances by a cam or lug P, carried by 85 link L, which passes behind a projecting part L² of said gate, swinging the latter forward, and returning passes in front of and out of contact with the gate. (See Fig. VII.)

The turning of the type to the proper position—that is, with the nicked side out or away from the operator—is effected by means of three trippers R R' R², Figs. IX and X. These trippers are in the form of curved fingers pivoted on pins r, attached to a horizontal flange of the back plate A and pressed by means of small springs p against the ledge or sill E, so as to exert a light pressure upon the type as it is fed along. Each finger is provided with a tooth q, projecting into the path 95 of one of the nicks of the type, so as to trip the type and cause it to make a quarter-turn, except when the nicked side is presented toward the tooth, in which case the latter fits in the nick and does not act. On the trippers 100 R R' the teeth are fixed; but the tooth q' on the third tripper R² is adjustable, so as to project a greater or less distance from the finger 105 R². This adjustment is necessary because the nicks of different fonts of type vary in 110 depth. The teeth q on the first two trippers need to project only a very slight distance to insure their action; but the third tooth q' should be adjusted so as to project a distance equal to the depth of the nicks. The reason 115 is that when the first two trippers are required to act they have a straight edge or corner of the type presented to them; but when the third tripper is required to act the type is always presented with its nicked side 120 forward, and the tooth consequently has a curved or notched edge to act against instead of a straight edge. To insure its catching and holding this edge until the type makes the full quarter-turn, it should project a distance 125 equal or nearly equal to the depth of the nick.

As shown in Fig. X, the tooth q' is formed on a spring-plate Q, attached to the back of finger R² by small screws s s', the tooth projecting through a slot in said finger. The plate Q tends to spring out away from finger 130

R^2 , and the extent of the projection of the tooth may therefore be regulated by tightening or loosening the adjusting-screws.

5 S is a holding-finger, similar in construction to the fingers R, but without any tripping-tooth.

S' is a gate, which the type pushes aside in entering the composing-stick, and which springs back after the type passes, Fig. VIII.

10 T is a lever pivoted on the screw-pin d and pressed by a spring t toward the composing-stick. It carries a spring-arm T', which presses lightly against the type as they rest against the rule U. Lever T can be swung out against the pressure of its spring t to give access to the type for the purposes of justifying, as shown in Fig. III. When swung out to the limit of its motion, it will remain in that position, being held by the pin t', which 15 is pressed by the flat spring u into the stop-hole u' in the frame or support A. The rule U forms a continuation of the sill E. It is held in place at one end by a little groove in the edge of the sill and at the other by the spring-latch v. It can be removed by lifting it up, so as to admit the line of type into the 20 space in front of it.

V is a friction-block which can slide in the composing-stick to accommodate additional 25 lines of type.

30 Heretofore the alarm-bell has been actuated by causing the line of type to force back the hammer against its spring until a certain point was reached, when the hammer fell. Such construction offered considerable resistance to the movement of the type, which in 35 the present machine is avoided.

According to this invention the holding-lever T, when swung back into place after the 40 line has been justified, retracts the bell-hammer until engaged by a dog or catch, and a very slight touch from the first of the line of type serves to trip the hammer and sound the bell. These devices are shown in Figs. 45 II, IV, and V. The bell-hammer 10 is pivoted at 11 to the under side of plate B and has a heel 12, in which is a small notch 13.

50 15 is a lever pivoted on pin 16 and connected by a link 17 with the hammer 10. The 55 latter connection is by a slot and pin. By turning lever 15 slightly on its center the hammer 10 is raised against its spring 20 until notch 13 is caught by the end of a dog 18, which is also pivoted on pin 16 and is controlled by a light spring 19. When lever 15 moves away from the bell, the dog 18 is compelled to follow by the contact therewith of pin 21. This reverse movement withdraws the dog 18 from notch 13, allowing the 60 hammer to fall.

65 The motions to the bell movement are communicated by a bent finger 23, connected to lever 15 by a screw-pin 24, passing through a slot in the finger and a slot in the lever. These slots intersect, so that the finger 23 can be adjusted in the direction of the type's movement and also transversely thereto. The

former adjustment is to cause the ringing of the bell at a longer or shorter time before completion of a line and the latter to provide for the tripping of the hammer by type of different thickness. When the holding-lever T is swung back to place, a depending bracket 25, fixed thereto, pushes back the finger 23, thereby turning lever 15 and raising the bell-hammer. 70 The end of finger 23 which overlies plate B has an inclined edge, and as the first type of the advancing line acts upon it lever 15 begins to turn in the reverse direction. The bell-hammer 10 does not partake of this motion of the lever, because of the slot in link 17; but when lever 15 has turned so far as to withdraw the dog 18 from notch 13 the hammer 10 falls upon the bell 28 and gives notice 75 that the line is nearly completed.

80 As already stated, the plate B is adjustably connected with support A by a set-screw a. This adjustment is provided in order that the machine may accommodate itself to different fonts of type. During its entire movement 85 the type rests on plate B, and to adjust the machine initially it is only necessary for the compositor to take one of the type he is about to use and raise or lower plate B until the teeth of the trippers register with one of the 90 nicks.

95 In operation the compositor seizes the type, as is customary, between the thumb and forefinger by the face end and brings it to the hopper. In this movement (whether of the 100 right or left hand) his disengaged fingers encounter the lever I and press it toward himself until the limit of its movement is reached, at which time the type will come in contact with the front wall of the hopper. He then 105 releases the type and lever, the latter dropping to the plate B and the former swinging back to its first position. At the next movement of the lever, when the feed-slide advances, the cam or lug P on link L opens 110 gate L', and fingers g feed the type forward along sill E, leaving it just in front of the tooth q of tripper-arm R. The next feed carries it past this tooth, by which it will be tripped unless the nick side be already 115 turned out. Thus the type advances by a separate movement past each tripper until finally it is pushed by the end g' of the feed-slide F past the gate S' into the composing-stick. When the line is full, of which due 120 notice is given by the alarm-bell, the compositor swings out the holding-lever T, thus exposing the type in a position convenient for justifying. When this has been done, he lifts out the rule U, drops it behind the line 125 just completed, and brings back lever T. In so doing lever T presses the rule until it snaps into place behind the spring-latch, the friction-block V yielding sufficiently to admit the newly-completed line of type. The 130 same motion of lever T resets the bell-hammer, and the apparatus is now in position to proceed with setting the next line.

Having now fully described the principles

of my said invention and explained the best means which I contemplate for applying the same, what I claim, and desire to secure by Letters Patent, is—

5 1. In a composing-machine, the combination, with a receptacle for type and with devices for turning the type on its longitudinal axis, of an actuating-lever pivoted in proximity to said receptacle, so as to be readily 10 operated in the act of depositing a type, substantially as described.

2. In a composing-machine, the combination of a receptacle for type and an actuating-lever pivoted adjacent to said receptacle 15 in position to be struck by the hand in the act of carrying a type to said receptacle, substantially as described.

3. In a composing-machine, the combination of a receptacle for type, feeding devices, 20 and an actuating-lever pivoted behind said receptacle and having two branches on the right and left thereof, respectively, substantially as described.

4. The combination of the feeding devices, 25 the receptacle, a pivoted gate closing the receptacle on the side toward which the type is to be fed, and a lug or cam for opening said gate as the feeding devices advance, substantially as described.

30 5. The combination of the feed-slide or carrier having fingers for advancing the type, a guide-pin carried by said slide, and a fixed ledge or sill provided with guideways in which said pin travels, the return-guideway 35 being curved to deflect the feed-slide and its fingers out of the path of the type, substantially as described.

6. The combination, with the reciprocatory feed-slide or carrier provided with a spring 40 guide-pin, of a fixed sill having a direct and a return guide-groove, which grooves meet at their extremities, with their bottoms in different planes, forming steps to switch the guide-pin from one groove to the other, substantially as described.

45 7. In a composing-machine, the combination of a series of trippers for acting successively upon the type and an intermittently-acting feed for carrying the type by successive motions past the several trippers, substantially as described.

50 8. In a composing-machine, the combination, with a series of trippers for acting successively upon the type, of a series of feed-fingers, one for each tripper, and means, such as specified, for actuating said fingers to carry the type by successive movements past the several trippers, substantially as described.

9. The combination of a series of trippers for acting successively upon the type, a movable slide or carrier having a series of feeding-fingers, one for each tripper, and actuating mechanism, such as specified, for moving said slide or carrier intermittently a distance approximately equal to the space between successive trippers, substantially as described. 60

10. The combination, with the type-feeding devices, of a series of tripping-teeth projecting into the path of the type in the line of one 70 of the nicks, substantially as described.

11. The combination, with the type-feeding devices, of a series of trippers, each composed of a narrow tooth rigidly attached to a yielding support and projecting into the path of 75 the type in line with one of the nicks, substantially as described.

12. In a composing-machine, the combination of a hopper or receptacle, a feed-slide or carrier provided with a series of feeding-fingers, tripping-teeth, each projecting from a yielding support into the path of the type, and a hand-lever connected with and actuating said feed-slide or carrier for feeding the type by successive movements past the several trippers, substantially as described. 80

13. The combination of the trippers carried by a stationary support, the type-feeding devices, and a plate upon which the type rest while being carried past the trippers, said 90 plate being detachably secured to said stationary support and adjustable vertically thereon, substantially as described.

14. The combination, with type-feeding devices, of a series of trippers comprising each 95 a tooth projecting into the path of the type from a yielding support, the tooth of the last tripper of the series being adjustably secured to its support, so that the extent of its projection may be varied, substantially as described. 100

15. The combination of the composing-stick, the rule, the lever for holding the line of type against the rule, the bell-hammer, a dog or catch for engaging a notch on said hammer, connections for raising the hammer when said 105 lever is swung into place, and a finger projecting into the path of the type for tripping said dog or catch and releasing the hammer, substantially as described.

In testimony whereof I have signed this 110 specification in the presence of two subscribing witnesses.

JOHN GUSTAFSON.
